UNITED STATES PATENT OFFICE.

ALFONSO C. VAN NIJS, OF CLEVELAND, OHIO.

TREAD-REST FOOT GRIP.

Application filed January 9, 1922. Serial No. 527,901.

To all whom it may concern:

Be it known that I, ALFONSO C. VAN NIJS, a resident of the city of Cleveland, in the county of Cuyahoga and State of Ohio, 5 and a citizen of the United States, have invented certain new and useful Improvements in Tread-Rest Foot Grips, of which the following is a specification.

This invention relates to foot grips for receiving foot coverings such as shoes and adapted to be secured to a stand, such as the iron stands usually found in shoe shining parlors. It is an object of this improvement to provide a cushioning pad for such 15 metal stands to give an easy rest for the shoes while they are being polished. It is a further object of the invention to make such pad of material which will prevent undesirable slipping of the foot covering upon 20 the pad. To this end the material used may be some rubber composition, though this is not essential. Cork or other cushion substances may be used as well. It is a further 25 object to provide the surface of this pad or foot grip with a corrugated surface to easily hold the foot in position. It is a further object to provide such foot grip with surfaces of different levels, so that the heel base may drop down below the rest for the sole. 30 It is a further object to provide means for adjusting the relative heights of the heel and sole of the pad and it is also an object to provide means for elastically securing the foot in position on the pad.

35 Other objects and advantages will appear in the following specification and the novel features of the invention will be particularly pointed out in the appended claims.

My invention is illustrated in the accompanying drawings forming part of this application, in which:

Fig. 1 is a side elevation of the tread rest foot grip in position on the stand, and with the shoe resting upon the pad shown in 45 dotted lines.

Fig. 2 is a bottom plan view of the preferred form of the device.

Fig. 3 is a central vertical section of the preferred form.

50 Fig. 4 is a vertical section of the preferred form taken on the line 4-4 of Fig. 3.

Fig. 5 is a cross section of the form shown in Fig. 2 and taken on the line 5-5.

Fig. 6 is a side elevation of a modified form of the device. 55

Fig. 7 is a front elevation of details shown in Fig. 6.

Fig. 8 is a longitudinal vertical section of the form shown in Fig. 6. 60

Fig. 9 is a side elevation of another form of the device, and Fig. 10 is a bottom plan view of the form shown in Figure 9. 65

In the embodiment of my invention illustrated in the drawings in which like reference characters denote like parts throughout the specification, A represents the tread rest foot grip as a whole, B represents the usual form of iron stand upon which my foot grip or pad is adapted to be applied, 70 and C represents the shoe to be polished, 75 in position upon the pad, with the heel set in the offset position at the rear.

The foot grip is composed of two parts, a sole 1 and a heel 2, the latter being in a position at a lower level than the sole to fit the usual offset heel of the stand. These 80 parts are usually made of material such as rubber composition, cork or a material having a surface of one of these materials, so that the usual shoe will cling to the pad. 85 My improvement is provided with means for securing the same to the stand and is shown in the preferred form, illustrated in Figures 1 to 4, as rubber loops 3 which are secured at their ends to the edge of the parts 1 and 2 by a suitable means such as 90 nails 8, or which may be replaced by a cement or if the parts 1 and 2 are rubber as well as the loops 3, the latter may be vulcanized directly to the pad. In any case, 95 the parts 3 and 4 are very expandable and flexible so that they will stretch sufficiently to apply the loops 3 over the toe of the stand and thereafter apply the loop 4 to the heel part.

Mechanism is also provided for adjusting the position of the heel of the pad to the sole where stands have a different depth of heel for receiving shoe heels of different heights. In the preferred form as shown 100 in Sheet 1, this adjustment is accomplished by securing to the heel of the pad metal

eyes 6 having extensions thereof embedded in the material of the heel, and also a metal plate 63^A projecting from the front lower edge. The sole part is then provided with 5 downwardly extending metal stems 5 which are threaded through the said eyes 6 and apertures in said metal plate, and terminate at their lower ends in loops 7. These stems may be made of steel and may be plated if 10 it is desired, or if it is preferred, they may be made of soft metal so that after the pad is placed in position on the stand the loops may be bent under the base of the stand so that they will avoid any possible obstruction to the polishing brushes or cloth in shining the shoe. These stems 5 may be secured to the sole piece by having bent ends embedded in the rear end of the sole, or they may be soldered to the metal piece 15 20 whose ends are bent around the side edges of the sole and secured by nails or otherwise. In some cases it may be desired to provide the pad as shown in Fig. 1 with other metal stems 5 of soft metal in other 25 portions of the sole or heel always near the edges of those parts, so that such stems may be bent under the iron plate as described in the application of the stems illustrated. The loop 4 is expandable as are 30 the loops 3 but is connected to the edges of the heel on three sides, being open at the forward edge only. It will be seen that there is thus formed a sort of hood by the part 4, since this is not to be applied to the 35 heel until after the sole is placed in position.

In the form shown in Sheet 2 is a modification, in which the loops of the preferred form are replaced by straps 11 provided with 40 buckles so that the foot grip may be applied to the stand and adjustably tightened thereto by the straps. These straps are looped about metal parts 12 that are secured to the body of the sole and heel by having 45 bent ends embedded therein or by nailing or screwing the same into the edge thereof. In this modified form, adjustment of the levels of the heel and sole is accomplished by securing the two parts together by a 50 very expandible rubber strip 10 secured above to the rear of the sole and below to the front edge of the heel. Stands having a varying depth of heel can be fitted by this 55 form by stretching the strip 10 to permit the heel part to drop into the proper position.

In the form of the device shown in Figs. 6 to 8, a triangular leather piece 15 is secured to the front edge of the sole of the 60 pad and is provided with lacing eyes 17 through which laces 16 may be threaded, the same looped backward around the leg of the stand and tied in position. Another eyelet 18 is provided near the tip of the 65 leather strip to which any ornament may be

secured or if it is desired for any reason in very large shops to number the various stands, a small metal check may be secured therein with twine or wire, the check bearing the number. 70

In the form shown in Figures 9 and 10 the leather 15 is dispensed with and a downwardly extended flange 13 which may be of rubber, leather or even of metal provided to bear against the toe of the stand. 75 At the rear of the heel is also provided a corresponding flange part 14. 15

While the embodiment of my invention is illustrated as comprising 3 separate forms in the drawings, it is expressly understood 80 that my invention is by no means restricted to such forms but comprises the conception of my improvements as stated in the objects of the invention and recited in the appended claims. For example, the straps shown in 85 Sheet 2 need not be used with the expandible band 10 or flanges 13 and 14, but may well be used in combination with the adjustable construction 5 and 6 of Sheet 1. Likewise, the looped construction 3 of Sheet 90 1 can evidently be used in combination with the band structure 10 of Sheet 2 or with the flange construction 13 and 14 of Figures 9 and 10; further, the flange parts 13 and 14 can be used with the 95 adjustable parts 5 and 6 of Sheet 1, and the leather device 15 can be used on any of the other forms, and the hood 4 of Sheet 1 can be used with the band connection 10 or with the straps 11. 100

It is also to be noted that it is contemplated using foot grips of different lengths to fit support stands of different sizes.

I may further use loops for either the sole or heel part, while straps may be used 105 on the other part of the same foot grip.

It is especially to be noted that while stems 5 may be used as a substitute for either the loops 3 or straps 11, as above indicated, such stems of soft iron need not be round in cross section but may well take the form of flat metal bands which may be bent under the stand in the manner referred to in describing such use for said stems when made of soft metal. Such metal bands may be used 115 on either the sole or heel part or both, the same being secured at one end to the edge of said part, the lower ends being adapted to engage the foot piece of the stand.

If in any case, it is desired to strengthen 120 the sole piece of the pad, a thin metal band may easily be imbedded therein; and if for any reason the roughened upper surface of the pad parts is not desired, as shown in the corrugated surface 19 of Fig. 4, such 125 surface may of course be left smooth as illustrated elsewhere.

While my tread rest foot grip is shown and described as adapted to be used as a 130 pad covering for shoe-shining stands, it

is by no means to be restricted to such use, but may be used wherever a cushioning pad is desired for any sole and heel surface whatsoever, as for example, on pedal operated brake levers, or pedal actuated levers for any purpose.

Having fully described my invention, what I claim as new and desire to secure by Letters Patent of the United States is:

1. A tread rest foot grip for shoe stands comprising in combination a sole pad and heel pad connected by adjustable means to permit variation of their relative positions when applied to stands having different depth of heel, means for detachably securing both sole and heel parts to the corresponding stand parts, the upper surface of said pad parts being roughened to efficiently hold the shoe in position thereon, substantially as described.
2. A tread rest foot grip comprising sole and heel parts flexibly connected together, the heel part positioned below the level of the sole part to suitably receive the corresponding parts of a shoe or boot, means attached to said parts for detachably securing them to the usual type of shoe-shining stand, the connection between the sole and heel parts including means for adjusting the height of the heel relative to the sole part, substantially as described.
3. A tread rest foot grip comprising in combination sole and heel parts flexibly connected together edge to edge, the heel part positioned below the level of the sole part to suitably receive the corresponding parts of a shoe or boot, expandible loops secured to the sole part and adapted to receive therein the toe part of a supporting stand and an expandible hood part secured to the heel part and adapted to enclose the heel of said stand and means for adjusting the height of the heel relative to the sole, substantially as described.
4. A tread rest foot grip comprising a cushion sole part and a heel part having the front edge of the heel flexibly connected to the rear end of the sole in combination with means for detachably securing both of said parts to a supporting stand.
5. A tread rest foot grip comprising sole and heel parts flexibly connected together, the heel part positioned below the level of the sole part to form an off-set seat to receive the heel of a shoe, and means attached to said parts for detachably securing them to the usual type of shoe shining stand,

the connection between the sole and heel parts including eye members in one of said parts, slidably receiving metal stems or rods in the other whereby the relative heights of the said heel and sole parts may be adjusted to fit stands having different depth of heel, substantially as described.

6. A foot grip comprising cushion sole and heel parts adjustably connected together to provide for footwear having heels of different height, substantially as described.

7. A cushioned foot grip comprising sole and heel parts of flexible material, the rear edge of the sole being adjustably connected to the front edge of the heel to fit shoes having heel of different height, substantially as described.

8. A foot grip comprising sole and heel parts adjustably connected together to provide for different relative position of sole and heel of footwear to rest thereon, and flexible means for securing said parts on a supporting element.

9. A tread rest foot grip comprising sole and heel parts adjustably connected together, the heel part positioned below the level of the sole part to form an off-set seat to receive the heel of a shoe, means including expandible loop parts for detachably securing the grip to a supporting stand, and mechanism for adjusting the heel part relative to the sole part comprising metal eyelet parts extending forward from the front edge of the heel part and receiving slidably therethrough metal stems secured at their upper ends to the rear edge of the sole part and terminating in loops at their lower ends, said stems being formed of soft metal to permit bending them under the support when the adjustment has been effected, substantially as described.

10. A tread rest comprising a plurality of adjustably connected pad parts each having soft metal stems for securing the said parts to a supporting element, said stems being adapted to be bent under the said element.

11. A tread rest comprising rubber sole and heel parts, the front edge of the heel being flexibly connected to the rear end of the sole, in combination with means for detachably securing each of said parts to a supporting element having surfaces corresponding to their normal levels.

In testimony whereof I hereunto affix my signature.

ALFONSO C. VAN NUIS.
